PEDAL TREAD

Harry Golden, Brooklyn, N. Y.

Application December 14, 1954, Serial No. 33,540

Term of patent 14 years

(Cl. D90—14)

To all whom it may concern:

Be it known that I, Harry Golden, a citizen of the United States of America, residing at Brooklyn, county of Kings, and State of New York, have invented a new, original, and ornamental Design for a Pedal Tread, of which the following is a specification, reference being had to the accompanying drawing, forming part thereof.

I claim:

The ornamental design for a pedal tread, as shown.
